UNITED STATES PATENT OFFICE.

THEODORE LUDWIG, OF NEW YORK, N. Y.

DESIGN FOR A CLEANING, SCOURING, AND POLISHING PAD.

56,760.

Specification for Design.

Patented Dec. 14, 1920.

Application filed July 2, 1920. Serial No. 393,722. Term of patent 14 years.

To all whom it may concern:

Be it known that I, THEODORE LUDWIG, a citizen of the United States, residing at New York, in the county of New York and State of New York, have invented a new, original, and ornamental Design for a Cleaning, Scouring, and Polishing Pad, of which the following is a specification, reference being had to the accompanying drawing, forming part thereof.

Figure 1 is a perspective view of my invention; and

Fig. 2 is a bottom plan view.

I claim:

The ornamental design for a cleaning, scouring, and polishing pad.

THEODORE LUDWIG.
